[57] CLAIM

The ornamental design for an intake reducing tee, substantially as shown and described.

DESCRIPTION

FIG. 1 is a perspective view of an intake reducing tee showing my new design;

FIG. 2 is a front elevational view thereof, the rear a mirror image of the front shown;

FIG. 3 is a top plan view thereof;

FIG. 4 is a bottom plan view thereof;

FIG. 5 is a right side elevational view thereof;

FIG. 6 is a left side elevational view thereof;

FIG. 7 is a perspective view of a modified form of the intake reducing tee shown in FIG. 1;

FIG. 8 is a front elevational view of FIG. 7, the rear being a mirror image of the front shown;

FIG. 9 is a top plan view of FIG. 7;

FIG. 10 is a right side elevational view of FIG. 7; and

FIG. 11 is a left side elevational view of FIG. 7.
